N. Stockwell.

Table.

N° 89,252.

Patented Apr. 20, 1869.

United States Patent Office.

NATHAN STOCKWELL, OF WINDSOR, NEW YORK.

Letters Patent No. 89,252, dated April 20, 1869.

IMPROVED TABLE.

The Schedule referred to in these Letters Patent and making part of the same.

To all whom it may concern:

Be it known that I, NATHAN STOCKWELL, of Windsor, in the county of Broome, in the State of New York, have invented a new and useful Improvement on Tables, or Work-Stands; and I do hereby declare that the following is a full and exact description of the construction and operation of the same, reference being had to the accompanying drawings, making a part of this specification, in which—

Figure 1 is a perspective view.

Figure 2, a sectional view of the pedestal and stand, representing the general arrangement of the working-parts.

Figure 3 shows the annular plate to which the legs are attached, and the manner of closing it.

Similar letters of reference indicate corresponding parts in each figure.

The nature of my invention consists in providing an adjustable central screw-standard for tables, or other similar purposes, capped with a nut and disk, which is attached to the centre of the lower surface of the table, and working in a sleeve and nut in the stand, so arranged that the table may be readily raised, or lowered, or turned around, and secured in position in such a manner as to insure more stability, with less liability to derangement, and which may be used in a more satisfactory and convenient manner than others now in use.

To enable others to make and use my invention, I will describe its construction and operation.

I construct my table, A, of wood, or other material used for similar purposes, with one or more tiers of drawers, B B, and an intermediate triangular recess, provided with drop-lids, C C, interlocking the body of the table with strips of wood at right angles with each other, and divide the top, A, into one or more parts, and hinge them together.

On the centre of the table may be attached a frame, D, for a looking-glass, or for pictures.

The pedestal, or stand, fig. 2, may be made of cast-iron, or other metallic substance, or of wood, with a metallic sleeve and nut, E, fitted into the body of the stand E, and secured by screws, G G.

I cut a thread on the central screw-standard H, to about half its length, leaving a shank, I, for the adjustable thumb-screw J to set against.

It will be seen, that in my invention, the screw-standard H works in the pedestal, or stand E, while, in other arrangements, it remains stationary in the stand, working in a nut in the body of the table, requiring a "cap" to cover its projecting end above the surface of the table. In my arrangement, the operation is reversed, and the surface may be made plain and unobstructed.

I screw the upper end of the screw-standard H into the thimble-nut in the centre of the disk K, until it meets the plate, which really gives to the top of the table sufficient steadiness and security; but, for the purpose of giving it additional security, I provide a jam-nut, L, and thumb-screw, m.

I also fit a thumb-screw, n, into the thimble-nut on the disk, which I attach to the centre of the lower surface of the table.

I attach the legs o o o o to the annular plate P, by means of notches in their edges, R R, and secure them in position with the wedge S, as represented.

The table may now be raised, or lowered, or turned around to any position desired, and securely held in place by means of the thumb-screw J.

I am aware that there are similar devices used for piano-stools and chairs, which require no device to hold them in a fixed position, while, in this arrangement, it is quite important that the table should be immovable on its axis, particularly when used to write upon, which is one of the purposes for which it is designed. This is effectually accomplished by means of the enlarged stem, or shank, I, of the screw-standard H, which is securely held in the sleeve-socket E by the thumb-screw J. This arrangement is only applicable to tables.

Having thus described my invention,

What I claim, and desire to secure by Letters Patent, is—

The combination of the table A, screw standard H, sleeve-socket E, and set-screw J, with the standard F, ring P, and legs O provided with the notches R and wedges S, all constructed and arranged substantially as set forth.

NATHAN STOCKWELL.
